UNITED STATES PATENT OFFICE.

WALTER SIMON, OF CHARLESTON, SOUTH CAROLINA.

DESIGN FOR A COLLAR.

41,904.

Specification for Design.

Patented Nov. 7, 1911.

Application filed June 3, 1911. Serial No. 631,138. Term of patent 7 years.

To all whom it may concern:

Be it known that I, WALTER SIMON, a citizen of the United States, residing at Charleston, in the county of Charleston and State of South Carolina, have invented a new, original, and ornamental Design for Collars, of which the following is a specification, reference being had to the accompanying drawing, forming part thereof.

The figure is a perspective view of a collar, showing my new design, the distinctive features of which reside in the angular

lower edges of the wings said wings terminating at their lower ends, approximately midway the width of the collar and in the broad or high extremities.

I claim:

The ornamental design for a collar, as shown.

WALTER SIMON.
